UNITED STATES PATENT OFFICE.

FERNANDO DE LIÑAN Y TAVIRA, OF MADRID, SPAIN.

CLOCK OR OTHER INDICATOR.

No. 887,257.

Specification of Letters Patent. Patented May 12, 1908.

Application filed October 5, 1905. Serial No. 281,564.

To all whom it may concern:

Be it known that I, FERNANDO DE LIÑAN Y TAVIRA, a subject of the King of Spain, residing at Madrid, in the Province of New 5 Castille, Spain, have invented new and useful Improvements in Clocks or other Indicators, of which the following is a specification.

My invention relates to clocks, watches, or 10 other indicators, and particularly to dials for the same.

The invention is designed to provide a dial for a clock, watch or the like, which will indicate the time in hours, minutes, etc., in 15 such a manner as to be instantly read without requiring close inspection.

The accompanying drawings will serve to illustrate a form of dial, etc. suitable for carrying my invention into effect. I wish it 20 understood, however, that I do not limit myself to the construction shown, as various changes may be made therein, or other forms employed, operating in substantially the same manner to produce practically the 25 same result.

In the drawings: Figure 1 is a face view of the clock dial illustrating my invention. Fig. 2 a view of the disk member containing the minute markings, and showing the 30 pointers, or hands, and Fig. 3 is a detail view of the minute hand.

Referring now to the drawings: A represents the fixed member of the dial, which is shown in the form of a ring, containing figures from 35 one to twenty-four, consecutively arranged and equi-spaced upon the same to represent the hours. It is evident, however, that I may divide the dial into the usual twelve hour divisions.

40 Mounted within the ring A there is a disk b, containing minute markings from one to sixty. This disk member b may be connected in any suitable manner with a time movement to be rotated once every twenty-four 45 hours and has fixed thereto a pointer a, arranged to coöperate with the hour markings upon the member A.

Coöoperating with the minute markings 50 upon the disk b, there is a hand or pointer c, which is connected to receive motion from the time movement above referred to and arranged to overtake the hour hand once every hour, thus indicating upon the disk b the fraction of the hour pointed out by the 55 hand a. The minute hand, therefore, moves at such a rate that it completes a revolution

and an additional amount sufficient to overtake the hour hand during each hour.

From the foregoing it will be seen that at the hour, the minute hand will lie directly over the hour hand and point in the same direction; at the half hour the hands will lie in the same straight line and point in opposite directions; at quarter past the hour, the position of the minute hand will be ninety degrees in advance of the hour hand, and at quarter to the hour, it will occupy a position ninety degrees at the opposite side thereof, being at right angles thereto in each instance. The reading of the dial is thus greatly facilitated, as the position of the hands relative to each other or the angle formed, serves to indicate the time with a fair degree of accuracy without requiring close inspection of the dial.

The operation, and advantage, of my invention will be apparent from the foregoing description.

Having thus described my invention, I claim:

1. In combination, a sectional dial, one section of which is fixed and graduated to indicate the fractions of a day and the other section of which is rotatable and graduated to indicate the fractions of an hour, a pointer 85 coöperating with the movable dial section to indicate the fraction of an hour, and a second pointer movable with the rotatable section and coöperating with the fixed section thereof to indicate the fraction of a day.

2. In combination, a sectional dial, one section of which is fixed and graduated to indicate fractions of a day and the other section of which is movable and graduated to indicate fractions of an hour, a pointer coöperating with the movable dial section, a second pointer carried by the movable section and coöperating with the fixed section thereof, and the movable section and the first-named pointer being movable in the same direction 100 at such relative speeds that the pointers will coincide on the hour, whereby the angular relation of the pointers will indicate the fraction of the hour.

3. An indicator comprising a fractional dial, the members of which each contain equi-spaced markings representing hours and fractions of an hour respectively, consecutively numbered, one of said members being fixed and the other rotatably mounted, a 105 pointer movable with the rotatable member and coöperating with the markings upon the

fixed member, a second pointer movable relatively to the markings upon the rotatable member, and the rotatable member and the second pointer being movable in the same direction at such relative speeds that the pointers will coincide on the hour and be opposite on the half-hour.

4. An indicator comprising a sectional dial, the members of which each contain 10 equi-spaced markings representing hours and fractions of an hour, one member being fixed and having the markings thereon consecutively numbered to represent the hours of a day, the other member being rotatably 15 mounted and having the markings thereon from one to sixty, a pointer movable with

the rotatable member and coöperating with the markings upon the fixed member to give hour indications, a second pointer movable relatively to the rotatable member and coöperating with the markings thereon to give minute indications, and the rotatable member and the second pointer being movable at such different relative speeds that the pointers will coincide on the hour.

20 25 In testimony whereof, I affix my signature, in the presence of two witnesses.

FERNANDO DE LIÑAN Y TAVIRA.
